UNITED STATES PATENT OFFICE.

FREDERICK ADOLPHUS BELLAMY, OF LONDON, ENGLAND.

AERIAL RECREATION APPARATUS, &c.

SPECIFICATION forming part of Letters Patent No. 663,004, dated December 4, 1900.

Application filed July 9, 1900. Serial No. 23,017. (No model.)

To all whom it may concern:

Be it known that I, FREDERICK ADOLPHUS BELLAMY, dental surgeon, residing at Holly Lodge, Streatham High Road, London, S. W., 5 in the county of Middlesex, England, have invented certain new and useful Improvements in Aerial Recreation Apparatus Applicable also for the Conveyance of Goods; and I do hereby declare the following to be a full, 10 clear, and exact description of the invention, such as will enable others skilled in the art to which it appertains to make and use the same.

This invention relates to improvements in aerial recreation apparatus applicable also 15 for the conveyance of goods, and has for its object to provide an apparatus adapted either for recreation purposes or for the conveyance of goods and merchandise from one given point to another, which apparatus in its form 20 as applied to recreation purposes will enable passengers to be conveyed through the air from a departure-platform to an arrival-platform at a very high rate of speed in such a manner as to afford the said passengers a 25 most exhilarating experience without any accompanying danger.

Furthermore, the invention is equally adapted for the rapid conveyance of goods and merchandise across rivers, precipitous 30 country, between warehouses, and under similar circumstances.

In the accompanying drawings, Figure 1 is 35 a side elevational view of the complete apparatus in its form as a recreation medium. Fig. 2 is a detail view of the car and its connections, Fig. 3 being a similar view of a convenient form of car releasing and checking device for employment with this invention. Fig. 4 is a plan view showing how two of my 40 amusement apparatus may be arranged side by side.

Referring to the drawings, wherein like letters represent corresponding parts throughout all the figures, *a* represents twin towers, 45 preferably of girder-work form, the space between which towers is spanned by a bridge or girder *b*, preferably having a central apex *b'*. The ends of the bridge or girder *b* are attached at *b*² to the towers *a*, the connecting-points 50 between the ends of the said bridge or girder and the towers being near the upper ends of same.

From the center of the bridge or girder *b* I suspend a single pendulum or two parallel pendulums or beams *d*, having attached at 55 their lower ends a passenger car or bob *e*, capable of always maintaining its horizontal position independent of the position assumed by the oscillating beams or pendulums aforesaid. 60

A platform *f* is provided upon each of the towers *a*, such platforms being arranged thereon to face each other. In connection with each platform is provided suitable releasing and checking or arresting devices, a 65 convenient form of which is shown by Fig. 3. This gravity catch device consists in a concave bed *g*, having slots *g'* provided therein one behind the other. Pivoted within these said slots at *g*² are toggles *g*³, the noses *g*⁴ of 70 which are adapted to normally project through the said slots *g'* and be above the surface of the bed *g*, while the tails of such toggles, in which corresponding recesses or notches *g*⁵ are provided, depend below the said bed. 75

Pivoted to the sides of the frame or case *h* of the arresting mechanism at *h'* I have two catch-arms *g*⁶, whose lower extremities are pivotally connected at *g*⁷ to a connecting-lever *g*⁸, through an opening in which one end of an 80 operating rod or lever *G* takes, said rod or lever being capable of ready removal therefrom.

The arresting mechanism before described operates in the following manner: When the 85 car or bob *e* reaches the arrival-platform at the end of its flight, it strikes the projecting noses of the toggles *g*³ and turns same on their pivots out of the operating position, causing them to fall forward in the direction the car 90 is proceeding and allowing the car or bob to pass over same until its momentum is expended and the point of inertia reached, whereupon such car or bob will endeavor to swing backward. The toggles in the meantime have automatically fallen into their normal position and prevent the retrograde movement of the car. The said toggles are prevented from being turned back upon their pivots by means of the noses of the catch-arms *g*⁶, which engage with the notches or recesses *g*⁵ in the toggles *g*³ and maintain such toggles in their upright or operative position 100 until the operating-rod *g*⁸ is disconnected from

the connecting-lever G, whereupon the weight of the car or bob is enabled to turn the said toggles back upon their pivots out of their arresting or operating position and so pass on its journey toward the opposite platform.

5 Although the before-described form of arresting and releasing device is a convenient one, I may employ any suitable equivalent in lieu thereof.

10 In operation the car or bob is raised to the required height (by manual, hydraulic, or other power) on one of the towers and released in the foregoing manner, whereupon it travels by its own momentum or gravitation until it 15 arrives at the platform upon the other tower, where the arresting mechanism comes into operation and retains the car or bob preparatory to its return journey. Before starting the said car or bob on a journey it is raised 20 above the platform to a suitable height in any well-known and desirable manner.

The lower or other desirable parts of each tower may be fitted up as refreshment-kiosks, waiting-rooms, or the like in the usual manner.

What I claim as my invention, and desire 25 to secure by Letters Patent, is—

In aerial recreation apparatus, the combination of two towers having platforms projecting from the opposing sides thereof, provided with car retaining and releasing devices and elevating mechanism of a bridge spanning the space between said towers; said bridge having its ends joined to the upper ends thereof, and having a central apex; and oscillating beams or pendulums swung from said bridge; and a car swung from the ends of said oscillating beams or pendulums, whereby it is always enabled to maintain its equilibrium irrespective of the position assumed by the oscillating beams or pendulums, substantially as specified.

In testimony whereof I hereunto affix my signature in presence of two witnesses.

FREDERICK ADOLPHUS BELLAMY.
